ABSTRACT OF THE DISCLOSURE

A fuel vapor adsorbing apparatus to prevent emission to the atmosphere of residual fuel vapors from a service station storage tank when such tank is filled. The adsorbing apparatus includes a hydrocarbon adsorbing means having its inlet connected with the upper portion of the storage tank whereby vapors expelled during filling of the storage tank will be passed through the adsorbing means to remove hydrocarbons therefrom to prevent emission to the atmosphere.

This invention relates to a vapor emission prevention and conservation system for motor vehicle fueling stations which will prevent the emission of hydrocarbon vapors to the atmosphere from such stations.

The emission of unburned hydrocarbon vapors to the atmosphere is known to be an undesirable source of air pollution. When hydrocarbon fuels are pumped into service station fuel supply tanks or into motor vehicle fuel tanks the liquid displaces vapors within such tanks which are customarily vented to the atmosphere. These vapors contain considerable amounts of hydrocarbon.

The object of this invention is to pass all vented vapors from such fueling operations through an adsorber wherein the hydrocarbon constituents are adsorbed in a suitable adsorbent material, thereby preventing their emission to the atmosphere.

Other objects will be apparent from the description, drawings and appended claims.

DESCRIPTION OF THE DRAWING

FIG. 1 is a schematic view of a fuel vapor adsorbing apparatus embodying the present invention;

FIG. 2 is a detailed view, partially broken away, of a modification of the adsorbing means included in the apparatus shown in FIG. 1;

FIG. 3 is a sectional view, in enlarged scale, of the outlet of the adsorbing means shown in FIG. 2;

FIG. 4 is a vertical sectional view of a coupling means for installation on the spout of a motor vehicle fuel tank; and

FIG. 5 is a vertical sectional view of a second embodiment of a coupling means for installation in the fuel spout of a vehicle fuel tank.

DESCRIPTION OF THE PREFERRED EMBODIMENT

In the drawing, FIG. 1 is a diagram of one arrangement of a fuel receiving, storing and dispensing system which provides for adsorption of displaced hydrocarbon vapors. To fill the fuel supply tank 1, the delivery truck tank 2 is connected to tank 1 by line 3 containing pump 4 and valve 5. Liquid fuel entering tank 1 via line 3 displaces vapors containing hydrocarbons some of said vapors flowing via line 6 to tank 2 and excess vapors, which are generated due to agitation of the liquid fuel, flowing via lines 7 and 8 to adsorber 9, thence via line 10 to adsorber 11, thence via line 12 to the atmosphere. Valve 13 in line 7 is normally closed, but for emergency use or to provide for maintenance may be opened thereby permitting flow to or from the atmosphere via line 7 and

2

pressure/vacuum relief valve 14. Vapors passing through identical adsorbers 9 and 11 contact granulated charcoal or other suitable material, which will adsorb hydrocarbon vapors while permitting air to pass through the adsorbent bed 15.

To fill a motor vehicle fuel tank 16, liquid fuel flows through line 17 containing pump 18 and terminating in a suitable vapor-recovery type fuel tank connection 19. Vapors displaced from fuel tank 16 flow via line 20 to line 7, thence via line 7 to fuel supply tank 1. Excess vapors generated by agitation, thermal changes, etc. flow via lines 20, 7 and 8 to adsorbers 9 and 10 wherein hydrocarbons are adsorbed as described above.

When the adsorber material in adsorber 9 is saturated, the cannister 21, which contains the saturated adsorbent material, is replaced with identical cannister from adsorber 11 and a cannister containing fresh or regenerated adsorbent material is installed in adsorber 11. This procedure provides a 2-stage adsorber wherein the second stage adsorber 11 always contains a less saturated adsorbent material than the first stage adsorber 9. This arrangement represents two stages of counter-current action, thereby providing for efficiency.

Cannisters containing saturated adsorbent material may be collected from many locations and taken to a centrally located facility for regeneration of the saturated adsorbent material, regeneration being accomplished by stripping hydrocarbons from the adsorbent material by passing superheated steam through it, with subsequent recovery of condensed hydrocarbon liquids.

FIG. 2 shows an alternate construction of adsorber wherein the adsorber consists solely of a removable cannister 22 filled with an adsorbent material. Cannisters like 22 can be used in place of cannisters 9 and 11 to provide a similar multistage arrangement.

FIG. 3 is an enlarged view of the inlet 23 or outlet 24 of cannister 22 showing a screen 25, which may be arranged in a conical or other suitable configuration, and which serves to retain the adsorbent material within the cannister.

FIG. 4 shows a motor vehicle fuel tank cap 25 with integral vacuum/pressure relief valve 26 and gasket 27 assembled and attached to the motor vehicle fuel tank inlet nozzle 28. This fuel tank cap prevents over or underpressurizing fuel tanks which have no open vent to the atmosphere, such tanks being desirable to facilitate displacement of vapors only to the vapor recovery system. This fuel tank cap also serves to maintain a vapor pressure slightly above atmospheric pressure in the fuel tank, thereby reducing the amount of vaporization of hydrocarbons during operation of the motor vehicle and/or when it is at rest.

FIG. 5 shows a vapor recovery type motor vehicle fueling connection wherein a normally open-to-atmosphere vent hole 29 in the motor vehicle fuel tank inlet nozzle 30 is blocked and effectively closed by the flexible insert 31, which is integral with the connector 32 when during fueling operations, said connector 32 is attached to the nozzle 31 in line of a fuel tank cap. During fuel operations, liquid fuel enters the tank via fuel hose spout 33 and displaced vapors exit from the tank to a vapor hose attached to hose connection 34 via holes 35, annular passage 36, and hole 37.

I claim:

1. Fuel vapor adsorbing apparatus comprising:
a fuel storage tank;
fuel vapor adsorbing means having an inlet and an exhaust port;
a conduit connecting said storage tank with said vapor adsorbing means inlet;
an automobile filling hose connected on one end with

said storage tank and including coupling means on its opposite end for being coupled with the filling spout of an automobile fuel tank; and
 a vapor return line connected on one end with said coupling means and on its opposite end with the upper portion of said storage tank whereby the vapor expelled from the automobile fuel tank during filling thereof may be returned to said storage tank and passed through said adsorbing means to adsorb the hydrocarbons therefrom to prevent emission into the atmosphere.

2. Fuel vapor adsorbing apparatus as set forth in claim 1 for use with an automobile including a fuel tank spout having a vent port near the mouth thereof and wherein:

said coupling means closely interfits said spout to seal said vent port to prevent escape of vapors there-through.

3. Fuel vapor adsorbing apparatus comprising:

a fuel storage tank; fuel vapor adsorbing means having an inlet and an exhaust port;

a conduit connecting said storage tank with said vapor adsorbing means inlet;

a fuel transfer line connected on one end to said storage tank and adapted to be connected on its opposite end to a truck tank;

10 a vapor return line for connecting the upper portion of said storage tank with the upper portion of said truck tank; and
 an automobile filling hose connected on one end with said storage tank and including coupling means on its opposite end for being coupled with the filling spout of an automobile fuel tank whereby vapor may be communicated between said storage tank and truck tank and any excess vapor may be passed through said adsorbing means to adsorb the hydrocarbons therefrom to prevent emission into the atmosphere.
